UNITED STATES PATENT OFFICE.

DARIUS TENNET PHILLIPS, OF CHICAGO, ILLINOIS.

COMBINED BURGLAR-ALARM, MATCH-SAFE, AND SASH-FASTENER.

SPECIFICATION forming part of Letters Patent No. 315,439, dated April 7, 1885.

Application filed September 15, 1882. (No model.)

To all whom it may concern:

Be it known that I, DARIUS TENNET PHILLIPS, a citizen of the United States, residing at the city of Chicago, Cook county, Illinois, have invented a new and useful Combined Match-Safe, Door and Window Fastener, and Burglar-Alarm, of which the following is a specification, reference being had to the accompanying drawings.

10 Figure 1 is a perspective view of the combined safe, fastener, and alarm when closed and ready for convenient insertion in the pocket. Fig. 2 is a side elevation showing the device in working position. Fig. 3 is a view of the 15 window-fastener; and Fig. 4 is a perspective view of the combined door-fastener and alarm, showing the percussion-fuse in position for explosion.

In Fig. 1, A is a rectangular box of small 20 dimensions, with one end, a, opening outward on a hinge, and the sides projecting slightly beyond the opposite and closed end.

B is a straight steel spring attached to the edge of the box near its top by a rivet at b, 25 and designed to be sprung away from the box at its free end and held in that position by the bent wire D, which can be elevated for that purpose. When the said wire is elevated, the part of it at which the letter D is placed will 30 protrude slightly beyond the extremity of the sides of the box, and when this part of the wire is subjected to a stroke or pressure toward the box the wire will fall and allow said spring to return to its position along and parallel to the top of the box with sufficient force 35 to explode the tape of the percussion-fuse F, which is placed beneath a small protuberance on the under side of said spring. Said bent wire D is bent at obtuse angles, as shown 40 in the figure, which lie in a plane parallel to and against the side A of said box, and is bent at a right angle at each extremity, the arm at the lower extremity being inserted through the box in holes in the sides so as to turn 45 freely therein, and the arm at the other extremity passing under the spring when elevated and serving to keep it elevated. Said percussion-fuse F is drawn from the interior of said box through a narrow opening in the 50 top of said box under said spring, and thence through a similar opening or slit in the protruding end of said top, thus leaving but one explosive exposed at a time.

E is a screw with a sharp end, for the purpose of insertion into the door case or jamb in 55 order to attach the device thereto. Said screw is attached to a pivot, which turns in holes in the extended sides of the box, thus enabling the screw to be folded up against the end of the box. The figure shows the screw in its 60 folded position. r is a rivet passing through the sides of the box, to hold in place the window-fastener (shown in Fig. 3) when not in use.

Fig. 2 shows the machine in operation. 65 P is a door opening toward the box.

J is the case or jamb with the instrument attached by the unfolded screw E. The spring B is elevated and held up by the bent-wire D. F is the percussion-tape in position for explosion, and b is the small protuberance on the 70 spring which explodes the tape. When an attempt is made to open the door P, it presses against the bent wire D and throws it back, and the hammer-like protuberance at the end of 75 the spring B striking on the tape F explodes it and gives the alarm. The dotted lines at the top of this figure (marked a) show the opened end at which matches are inserted and removed.

80 Fig. 3 is a view of a combined button-hook and window-fastener.

c is a button-hook, which is inserted in the match-box at the open end thereof, and retained therein between one edge of said box 85 and a rivet passing through the sides of said box, and C is a sharp screw by which the instrument is inserted into the case or sash so as to prevent the lower sash from being raised. This instrument is detached from and independent of the box A and its appliances.

89 Fig. 4 is a perspective view of a top and end of the machine when loaded and cocked, but detached from the door.

E is the screw by which the machine is to 95 be attached.

e is the pivot forming base of screw and means of attachment to the box A.

F is the percussion fuse or tape, and F' is 100 the end of said fuse drawn through the slit in the protruding end of the top of the box.

D is the bent wire or trigger holding the spring B away from the box.

b' is the rivet securing the said spring to the 105 box, and b is the protuberance for exploding the percussion-tape F.

e' e' are slots for the passage of the tape F.
Having thus described my invention, what I claim, and desire to secure by Letters Patent, is—

- 5 The combination of a burglar-alarm consisting of the spring, the wire catch, and the fuse with and by means of a match-box provided

with a screw for securing said box and alarm to and in their operative position on a door-frame, substantially as described.

DARIUS TENNET PHILLIPS.
